UNITED STATES PATENT OFFICE.

HENRY FISCHER, OF NEW YORK, N. Y.

STEAM ROCK-DRILL.

SPECIFICATION forming part of Letters Patent No. 359,143, dated March 8, 1887.

Application filed July 22, 1886. Serial No. 208,739. (No model.)

To all whom it may concern:

Be it known that I, HENRY FISCHER, a citizen of the United States, residing at New York, in the county and State of New York, 5 have invented new and useful Improvements in Steam Rock-Drills, of which the following is a specification.

My invention relates to improvements in steam rock-drills; and it consists in certain 10 novel features of construction, which are fully pointed out in the following specification and claims, and illustrated in the accompanying drawings, in which—

Figure 1 represents a longitudinal central section of a rock-drill embodying my invention. Fig. 2 is a transverse section thereof in the plane $x x$, Fig. 1. Fig. 3 is a longitudinal section in the plane $y y$, Fig. 2. Fig. 4 is a transverse vertical section in the plane $z z$, Fig. 1. Fig. 5 is an inverted plan view of the valve-chest of the rock-drill. Fig. 6 is a horizontal section in the plane $x' x'$, Fig. 1. Fig. 7 is an elevation of the valve detached.

Similar letters indicate corresponding parts. 15 In the drawings, the letter A designates the cylinder of a steam rock-drill.

B is the plunger or piston which works in the cylinder.

C is the valve-chest having a cylindrical 20 bore.

$a a'$ are the steam-ports leading from this valve-chest to the respective ends of the cylinder A.

D is the valve fitted in the valve-chest.

E, Figs. 1 and 2, is the admission-port for 25 the entrance of live steam into the chest, and F, Fig. 2, is the exhaust-opening which leads from said valve-chest.

The valve D, Figs. 1, 2, and 7, consists of 30 two circular heads, $d d'$, which closely fit the cylindrical bore of the cylinder, and are connected by an eccentric shank, d' , which contains a port, f , that connects with a horizontal channel, f' , situated in the center of the valve 35 and extending through its heads d . This channel f' is in line with and communicates with the exhaust-opening F of the valve-chest, so that the exhaust-steam entering the valve from the cylinder A can freely make its escape 40 through said valve.

Around the shank of the valve D and be-

tween its heads $d d'$ is formed an isolated steam-space which communicates with the exhaust-ports $a a'$ of the cylinder, so that when either of said ports $a a'$ are uncovered live 55 steam from the boiler can freely enter the cylinder at the proper end. The bottom of the shank d' , which is flush with the periphery of the heads is in a steam-tight contact with the wall of the steam-chest, and the port f therein 60 is so located that when one of the ports $a a'$ is open the port f in the valve opens on the other port. By imparting to the valve D a reciprocating rocking motion the plunger is moved to reciprocate in its cylinder. To prevent 65 leakage about the valve from wear I make the bore of the valve-chest slightly tapering and turn the valve up correspondingly, so that it can be drawn inward to take up for wear. In this example I automatically impart this motion to the valve by the following means.

In the walls of the cylinder and to either side of the center line of the ports $a a'$ are formed two small auxiliary cylinders, G G', Figs. 2, 3, 5, and 6, which are connected with 75 the cylinder A by steam-channels $g g'$. In these cylinders are spring-pressed pistons $g^2 g^3$, the vertical rods of which are in contact with a diametrical rib or projection, h, Figs. 2, 5, and 7, on the face of the head d of the valve 80 D, so that as steam is admitted to one of the auxiliary cylinders G G' its piston is raised, and the valve D is turned to open one of the ports, and vice versa. The channels $g g'$ are opened and closed to admit steam to the 85 respective auxiliary cylinders by the movement of the piston, as usual with steam-actuated valves.

To regulate the length of the arc through which the valve is rotated by the pistons, I 90 use two set-screws, $i i'$, Figs. 2 and 3, that enter the valve-chest from above and are engaged by the rib or projection h on the valve D. By setting these screws in the proper manner the steam may be caused to expand more or 95 less in the cylinder.

To exhaust any steam which may enter the auxiliary steam-cylinders above their pistons, I connect the said cylinders with the exhaust-port f by small channels $j j'$, Figs. 3 and 5, extending through the wall of the valve-chest between the head of the same and the head d of 100

the valve D, and said space between the head of the valve-chest and the valve is in communication with the port f by a hole or channel, l, extending transversely through the head d 5 of the valve.

To control the stroke of the piston by hand I attach a shaft, b, to the valve, which extends through the casing and carries a hand-wheel on its outer end.

10 To turn the plunger B at the proper intervals I bore out the plunger at m, Figs. 2 and 4, to allow the entrance of a shank, M, having therein a number of helical grooves, m', which are engaged by balls m², contained in the end 15 of the piston, said balls being free to rotate, whereby an almost frictionless contact is obtained. The shank M is held stationary as the piston moves on its upward or non-working stroke, and consequently the plunger turns. To 20 accomplish this I provide the rear end of the shank M with an enlarged portion or friction-wheel N, Figs. 1 and 4, which is fitted into the cylinder-head A', and a groove therein is engaged above and below by wedge-shaped keys N' N', 25 which are inserted in keyways in said head, and are subjected to the action of springs n', and said keys can be adjusted by means of set-screws n² bearing upon the springs. When the friction-wheel is strained to turn in a direction opposite to arrow 1, Fig. 4, the keys are drawn inward in the keyways, and are consequently forced upon the friction-wheel, thereby binding the same. The wheel when strained in the direction of arrow 1, Fig. 4, 30 draws the keys outward, whereby they are released from said wheel and the latter can rotate freely. When the shank M is held stationary, the plunger is turned, and vice versa.

A steadyng-disk, n³, is attached to the shank 40 M, which turns in the end of the cylinder and affords a larger bearing.

What I claim as new, and desire to secure by Letters Patent, is—

1. The combination, with a cylinder and its 45 ports, of a valve-chest having a cylindrical bore, a valve fitted to said bore, an exhaust-port extending through said valve and opening to receive and discharge the exhaust-steam from the ports of the cylinder, and auxiliary

steam-actuated pistons reciprocated alternately in opposite directions for rocking the valve, substantially as set forth.

2. The combination, with a cylinder and its ports, of a plunger fitted in the cylinder, a valve-chest, a valve fitted therein, the auxiliary cylinders G G', opening to the cylinder, the pistons g² g³ in said cylinders, and the rods on said pistons engaging the valve to rock the same, substantially as set forth.

3. The combination, with a cylinder and its 60 ports, of a plunger fitted in the cylinder, a valve-chest, a valve, D, fitted in said chest, the exhaust-ports f f' therein, the projection or rib h on the face of the valve, the auxiliary cylinders G G', the channels communicating 65 with the cylinder and the auxiliary cylinders and opened and closed by the motion of the piston, the spring-pressed pistons g² g³ in said cylinders, the rods thereof engaging the rib or projection on the valve, and the set-screws 70 i i', for regulating the vibrations of the valve, substantially as set forth.

4. In a rock-drill, the combination, with the cylinder, of a recessed plunger, B, fitted therein, the balls m² in said plunger, the shank M, 75 having grooves engaged by the balls, the grooved portion or wheel N on said shank, and the keys or wedges engaging said grooved portion, substantially as shown and described.

5. In a rock-drill, the combination, with the 80 cylinder and the recessed plunger therein, of a grooved or threaded shank, M, having a bearing at one end of the cylinder and engaging the plunger with its free end, a grooved wheel or portion at the bearing end of the 85 shank, and the spring-pressed wedges or keys bearing upon the fixed portion of the shank to prevent the rotary motion of the same in one direction, substantially as shown and described.

In testimony whereof I have hereunto set my hand and seal in the presence of two subscribing witnesses.

HENRY FISCHER. [L. S.]
